BOTTLE FILLING MACHINE VALVE

James Kantor, Chicago, Ill., assignor to The Liquid Carbonic Corporation, Chicago, Ill., a corporation of Delaware

Application April 25, 1938, Serial No. 204,014

13 Claims. (Cl. 226—122)

My invention relates to improvements in bottle or container filling machines and particularly to the filling valve used in conjunction with such a machine.

More particularly, my invention relates to an improvement in a filling valve of the type wherein there is provided a rotary valve controlling member for controlling the admission of counter-pressure to the bottle, to initially exhaust the air therefrom, controlling the admission of the liquid to the bottle and eventually "sniffting" the bottle after the same has been filled.

In certain of the rotary type valves for accomplishing the above results, the valve structure is such that the parts have to be made unnecessarily large, thereby increasing considerably the frictional resistance to the turning effort of the valve and also increasing materially the wear of the valve parts.

It is one of the objects of my invention to so construct a valve having the above characteristics that the parts may be reduced materially in size and the frictional wearing thereby materially reduced, to say nothing of the other more specific advantages.

For the purpose of disclosing my invention, I have illustrated an embodiment thereof in the accompanying drawings in which:

Fig. 1 is a sectional view of a portion of so much of a filling machine as is necessary for the illustration of my invention;

Fig. 2 is a side elevation of a valve embodying my invention;

Fig. 3 is a longitudinal sectional view of the valve showing the same in "snift" position;

Fig. 4 is a longitudinal sectional view of a valve embodying my invention, showing the parts in counter-pressure position;

Fig. 5 is a longitudinal sectional view showing the liquid control valve of operating mechanism in filling position;

Fig. 6 is a detail sectional view showing the valve controlling mechanism in filling position;

Fig. 7 is a sectional view on the line 7—7 of Fig. 2;

Fig. 8 is a detail section on the line 8—8 of Fig. 3;

Fig. 9 is a detail section on the line 9—9 of Fig. 3;

Fig. 10 is a detail section on the line 10—10 of Fig. 5;

Fig. 11 is a detail section similar to that shown in Fig. 10, with the valve being shown in open position;

Fig. 12 is a detail longitudinal sectional view

of the discharge end of the filler tube; and Fig. 13 is a sectional view on the line 13—13 of Fig. 4.

In the embodiment of the invention illustrated, the filling machine includes a filling tank 1 adapted to contain the carbonated water with which it is intended to fill the bottle or other container. This container or tank is provided with suitable float valves 2 and 3 controlling the admission to or the escape of carbon dioxide gas into the top of the tank and above the water contained therein. Water is supplied to the tank through the medium of a water supply pipe 5, the arrangement being such that the tank and its associated parts can be rotated. Preferably, in this type of filling machine, the admission of water into the tank is controlled by the counter-pressure of the CO₂ admitted thereto. It will be noted that with the float of the valve 2 in its lower position, this valve is closed and, therefore, CO₂ cannot be admitted to the tank. Therefore, with the pressure in the tank comparatively low, the water will flow thereinto. As soon, however, as the water has reached its desired level, thereby raising the float controlling the valve 2, this valve will be opened, permitting the admission into the tank of sufficient CO₂ under the proper pressure to counter-balance the flow of the water into the tank, thereby cutting off the water flow.

This tank has mounted thereon a series of filler valves 6 adapted to rotate with the tank 30 and each being adapted to receive from the tank a supply of liquid through the pipe 7 and a supply of CO₂ through the pipe 8. The filling valve, generally considered, consists of a head 9 having secured thereto a downwardly extending stem 10. 35 This stem is flanged as at 11 at its upper end and receives a coupling nut 12 screw threaded to the head 9. The lower end of this stem 10 receives and supports the filler tube 13 which, in effect, comprises two tubes, the outer tube 14 through which gas is admitted to and withdrawn from the container to be filled and the inner tube 15 which telescopes the outer tube. This inner tube 15 is provided with a longitudinally extending passage 16 on its outer surface, through which the gas may be passed to the bottom of the tube and escape through the openings 17 in the outer tube. The lower end of the inner tube is closed by a valve 18 having a seat 19 adapted to engage the bottom end of the tube 15 and provided with an annular flange telescopically receiving the bottom end of the tube and provided with an escape opening 20.

A bottle bell 21 is slidably mounted on the filler tube 13 and at its lower end is provided with

a bell-shaped opening 22 to receive the bottle. This bell, in its normal position, is at the lower end of the tube, as illustrated in Fig. 2, but when the bottle is raised through suitable instrumentalities, the neck of the bottle enters the bell mouth, making sealing engagement with the sealing washer 23 and raises the bell 21 until it makes sealing engagement with the sealing washer 24. This bell mouth does not tightly surround the filler tube 13, there being left between the filler tube and the washer, a suitable passage 25, the purpose of which will more fully appear hereinafter.

The liquid delivery pipe 7 makes engagement with the threaded boss 26 on the head 9 and delivers through the opening 27 therein and the hand-controlled valve 28 into the chamber 29 at the top of the head. The gas or counter-pressure supply pipe 8 is connected to a similar boss 30 on the head 9 which communicates by the opening 31 with a chamber 32 from which counter-pressure is delivered through the valve to the container.

The filling valve is provided with a valve operator 33 having an upper arm 33' and a lower arm 33''. This valve operator is adapted to manipulate the valve mechanism for controlling the admission of counter-pressure to the bottle to be filled, the admission of the liquid to the bottle and the "snifting" of the bottle after the filling operation has taken place. In machines of this character, the lower arm 33'' is adapted to engage suitable stops arranged in its path of movement for the purpose of moving the same into certain predetermined positions. Likewise, the arm 33' is adapted to engage suitable stationary stop, in the path of the movement of the valve, for moving the valve mechanism into certain predetermined positions. The positions to which the arms 33' and 33'' are moved are indicated in full and dotted lines in Fig. 2. Referring to this figure, when the arms are in the position shown by full lines, they are in the "snifting" position. The second position is indicated by the next position to the left in dotted lines as being the counter-pressure position and the final position indicated by the dotted lines is the filling position.

As illustrated in Fig. 4, the pipe 8 and, therefore, the top of the tank 1 is adapted to be placed into communication with the valve when the bottom of arm 33 is moved, by the engagement with the stop, to the position indicated in Fig. 2 as the counter-pressure position. It will be noted that the chamber 32 is connected by a passage 32' with a face 34 on the head 9. This face, in turn, is connected by a passage 35 in the stem portion of the valve which, in turn, is connected with a passage 36 in the stem portion 10 which passage 36, in turn, is in communication with the passage 16 in the inner tube 15 of the filler tube 13. For controlling communication between the passages 35 and 32', I provide a rotatable valve member 37 which is rotatably mounted within an annular flange or sleeve portion 38 on the head 9, which valve member is provided with a conduit 39, within its body, in communication with a passage 40, a second passage 41 somewhat reduced in diameter relatively to the passage 40, and with a third passage 41'. In order to insure a liquid tight joint between the face of the rotatable valve member 37 and the face 34 of the head 9, I interpose between these faces a packing disc 42 which may be of leather or other suitable material, and this disc, it will be noted, is provided with openings therein coinciding with the passages 32' and

35. Suitable nipples 43 pass through the openings in the washer and into the passage openings. This rotatable valve member 37 is rotatably mounted upon a spindle 44 in the valve head 9. The valve member 37 is provided with an annular flange or extension 45 which overhangs a collar 46 surrounding and keyed to the spindle 44. Interposed between this collar and the valve member 37 is a resilient member in the form of a rubber ring 46' which maintains the packing disc 42 in close contact with the face 34. The collar is moved toward the valve member 37 by a nut 47 screwed on the end of the spindle 44 and by turning this nut up sufficiently tight, a tight joint is made between the face of the valve member 37 and the packing disc 42. The collar 46 has a pair of radial arms 48 and 49. The arm 48 is arranged in a slot 50 in the hub of the lever 33 and the arm 49 extends between a pair of bosses 51 on the annular flange 45 of the valve member 37. Suitable adjusting screws 52 extend through these bosses and bear against the arm 49 so that a nice adjustment of the relationship between the disc 37 and the operating member 33 may be obtained. This arrangement provides a driving connection between the operating member 33 and its associated arms 33' and 33'' and the spindle 44 and valve member 37, whereby the spindle 44 and the valve member will be rotated in unison with the operating arms.

In addition to the passage 36, the stem 10 and associated part 9 has a passage 53 likewise communicating with the top of the gassing tube 13 through passages 39 and 53', which passages in the filling position of the valve are adapted to be placed in communication with the port or opening 41' and thereby, as is the case in the counter-pressure position, placing the bottle in communication with the top of the tank 1 and therefore in communication with the counter-pressure zone. The establishment of this communication takes place when the valve has been rotated to the furthest movement, as indicated in Fig. 2 in dotted lines, to the filling position.

The valve member 18, for controlling the flow of liquid through the tube 15 is operated through the medium of a stem or rod 54 which extends upwardly through said tube and terminates at its upper end in a cap 54' threadedly mounted on the rod. Interposed between this cap and a shoulder 55 is a coiled spring 56 which biases the valve in its closed position. The chamber 29 communicates through the passageway 29' in the head 9 with the tube 15 and arranged in this chamber is a valve 57 biased in its closed position by a coiled spring 58 which tends to move the valve downwardly and on its seat 59. When seated, communication from the chamber 29 is closed to the passageway 29'. The valve 57 is provided with a downwardly extending stem 60 which extends toward the cap 54'.

Interposed between the cap 54' and stem 60 is a cam member consisting of a pair of radial arms 61 and 62 mounted on the spindle 44. These arms are adapted to respectively contact with a pair of swinging members 63 and 64, the ends of which are interposed between the cap 54' and the stem 60 so that when the cam member, with its arms 61 and 62, is in one position, both of the valves 51 and 18 are opened, and when in their crosswise position, these valves are closed. The timing is such that the valves are moved to their open position at the same time that communication is established between the passage 53 and the port 41'. Therefore,

when the valves 57 and 18 are in their open position to permit the flow of liquid from the tank into the bottle, the counter-pressure tube is placed in communication with the top of the tank and the gas heretofore introduced into the bottle is allowed to flow back into the tank.

After the bottle has completed its rotative movement with the tank 1 until it has become filled, the upper arm 33' of the operating lever 10 33 engages a stop, arranged in the path thereof, moving the upper arm to rotate the valve member in a counter-clockwise direction, therefore closing the filler valve and the counter-pressure passages. At the same time the passage 65, in 15 communication with the top of the bell 21 is placed in communication with a "snift" passage 65' leading to the atmosphere through the medium of a passage 66 in the valve member 37 and a pair of ports 67 and 68.

20 It is apparent, from the above structure, that the number of ports to be controlled by the rotary valve member 37 is reduced to the minimum because the liquid control valve which under certain commercial circumstances heretofore in practice has also been controlled through this rotatable valve member is now controlled by the pair of valves 18 and 57 operated in turn by the cam members 61 and 62.

I claim as my invention:

30 1. The combination in a filling head of a valve body, a spindle rotatably mounted in said body, an annular flange on said valve body surrounding said spindle, a rotatable valve surrounding said spindle and arranged within said flange, a 35 driving arm for said spindle mounted on said annular flange a driving connection between said driving arm and said spindle and a second driving connection between said spindle and said valve.

40 2. The combination in a filling head of a valve body and a valve rotatably mounted upon said body, the valve and valve body being respectively provided with corresponding passages adapted to be placed in alignment upon rotation of the 45 valve, an axially stationary spindle carried by said valve body, said valve being mounted upon said spindle and adjustable axially thereon, means for adjusting said valve axially on said spindle, and a driving connection between said 50 adjusting means and said valve, permitting relative axial movement between said valve and adjusting means while insuring a rotating driving connection between the same.

3. The combination in a filling head of a 55 valve body and a valve rotatably mounted upon said body, the valve body and valve being respectively provided with corresponding passages adapted to be placed in alignment upon rotative movement of the valve, a spindle mounted upon 60 said valve body and carrying said rotatable valve, a driving means drivingly connected with said spindle, and a driving connection between said spindle and said valve, said connection having means for rotatably adjusting said valve 65 relatively to said driving means.

4. The combination in a filling head of a valve body having a series of passages therethrough leading to one face of the valve body, a filling nozzle on the filling head including a pair of 70 telescoping tubes, passages leading from one of said tubes to said face of the valve body, an additional passage in said body leading to the other of said tubes, a reciprocating valve controlling the flow through said second-mentioned 75 tube, a rotary valve on said valve body face

having parts therein adapted upon rotation of said valve to bridge corresponding passages in said valve body leading to said face and means operated by the rotation of said valve for coincidentally and mechanically operating said reciprocating valve.

5. The combination in a filling head of a valve body having passages leading to one face of the valve body, a filling nozzle on said head including a pair of telescoping tubes, said valve body having additional passages therein leading from said face to the outer of said telescoping tubes, a spindle rotatably mounted on said head, a valve rotatable with said spindle and cooperating with said face, said valve having 10 passages therein adapted to bridge certain of the passages in said valve body, an additional passage in said valve body communicating with the inner of said telescoping tubes, a valve controlling the passage of liquid through said inner tube and a cam member carried by said spindle and adapted to operate said valve coincidentally with said rotary valve.

6. The combination in a filling head of a valve body, said body having a series of passages leading to a face thereof, a filling nozzle on said filling head comprising a pair of telescoping tubes, a second set of passages leading from said face to the outer of said telescoping tubes, a rotary valve having passages therein arranged to connect, 30 upon rotation thereof, said two sets of passages, said valve body having a passage therethrough communicating with the inner of said tubes, a valve closing the rear end of said inner tube, a second valve controlling the admission of liquid 35 to said inner tube passage, a rotary spindle carrying said rotary valve and cam means on said rotary spindle arranged to operate said last two mentioned valves coincidentally with the operation of said rotary valve.

7. The combination in a filling head of a counter pressure tube and a liquid delivery tube, a reciprocating valve controlling the flow of liquid through said liquid tube and a rotary valve controlling the flow through said counter-pressure tube, and common actuating means for rotating said rotary valve and operating said reciprocating valve.

8. The combination in a filling mechanism, of a filling head comprising a body portion having a plurality of flow passages therein, a reciprocating valve controlling the flow through one of said passages, the remaining passages terminating in the face of said body, a rotary spindle extending through said body, a cam on said spindle for operating said vertically movable valve, a rotary disc valve surrounding said spindle having a driving connection therewith and having flow passages therein adapted to coincide with the flow passages terminating in the face of the valve body, an operating arm rotatably mounted on said valve body independently of said spindle and a driving connection between said arm and said spindle.

9. The combination in a filling mechanism, of a filling head comprising a body portion having a plurality of flow passages therein, a filling tube connected with one of said flow passages, a reciprocating valve controlling the flow through said tube, certain of said passages terminating 70 in the face of said body, a second tube surrounding said first-mentioned tube and adapted to receive the flow from said second-mentioned passages, a rotary spindle extending through said body, a cam on said spindle for operating said 75

- vertically movable valve, a rotary disc valve surrounding said spindle and having flow passages therein adapted to coincide with the face terminating flow passages, a driving connection between said spindle and said valve, an operating arm rotatably mounted on said valve body independently of said spindle and a driving connection between said arm and said spindle.
10. The combination in a filling mechanism, of a filling head comprising a body portion having a plurality of flow passages therein, a reciprocating valve controlling the flow through one of said passages, the remaining passages terminating in the face of said body, a rotary spindle extending through said body, means on said spindle for operating said vertically movable valve, a rotary disc valve surrounding said spindle and having flow passages therein adapted to coincide with said face terminating flow passages, means for limiting the movement of said spindle axially at least in one direction, clamping means secured to the free end of said spindle, means interposed between said clamping means and said valve for biasing the valve against the face of said body, an operating arm rotatably mounted on said valve independently of said spindle, a driving connection between said arm and said spindle and a driving connection between said spindle and said valve.
20. 11. The combination in a filling mechanism, of a filling head comprising a body portion having a plurality of flow passages therein, a reciprocating valve controlling the flow through one of said passages, a rotary valve controlling the flow through the remaining of said passages, a rotary spindle extending through said body, operating means on said spindle for operating said reciprocating valve, said spindle having a bearing in said body on each side of said operating means
- 5 and a driving connection between said rotary valve and said spindle.
12. The combination in a filling mechanism, of a filling head comprising a body portion having a plurality of flow passages therein, a reciprocating valve controlling the flow through one of said passages, the remaining of said passages having terminations in the face of said body, means on said spindle for operating said reciprocating valve, an annular flange on said body, a rotary disc valve mounted within said flange and surrounding said spindle and having flow passages adapted to coincide with said face terminating flow passages, a driving connection between said spindle and said valve, an operating arm mounted on said annular flange and a driving connection between said arm and said spindle.
- 10 15
13. The combination in a filling mechanism, of a filling head comprising a body portion having a plurality of flow passages therein, a filling tube connected with one of said flow passages, a reciprocating valve controlling the flow through said tube and a second reciprocating valve controlling the flow into said tube, a second tube surrounding said first-mentioned tube adapted to communicate with the other of said flow passages, said other flow passages having a termination in the face of said body, a rotary spindle extending through said body, cam means on said spindle for operating said reciprocating valves, a valve disc 20 25 surrounding said spindle and having flow passages therein adapted to coincide with the face terminating passages, means for biasing said disc against said face, an operating arm rotatably mounted on said body independently of said spindle, a driving connection between said arm and said spindle and a driving connection between said spindle and said disc valve.
- 30 35

JAMES KANTOR.
